CALENDAR CLOCK

Victor Anderson, Jerome, Idaho

Application October 22, 1948, Serial No. 55,907

2 Claims. (Cl. 58—6)

1

My present invention relates to an improved calendar clock of the type including a clockwork mechanism of the spring wound or electric type having the customary face and hands and having in addition, visible through an aperture in the clock case, a rotary drum showing the days of the week and a tape showing the days of the months, and unique operating mechanism for the drum and tape so that the movement of the drum and tape from one day to the next will take place over a short period of time and the device is adapted to be adjusted to provide for such movement at or near the midnight hour.

The calendar operating mechanism of the clock of my invention need be set only once a year, either on the first of January, or if preferred it may be set on the 28th day of February, and in the former case it of course must be reset on the 29th of February in leap years while in the latter case will be set on the 28th and 29th of February as may be required.

In the accompanying drawings I have illustrated one complete example of the physical embodiment of my invention according to the best mode I have thus far devised but it will be understood that various changes and alterations may be made in the exemplified structure within the scope of the appended claims.

In the drawings:

Figure 1 is a front elevational view of the calendar clock of my invention.

Figure 2 is a horizontal sectional plan view thereof of the upper idler shaft of the tape holding casing being broken away to show a clutch assembly on the tape driving shaft below.

Figure 3 is a vertical sectional view through the casing.

Figure 4 is a transverse vertical sectional view taken on line 4—4 of Figure 2 showing the tape feed.

Figure 5 is a transverse vertical sectional view showing the tape drive mechanism.

Figure 6 is a side elevational view of the tape drum.

Figure 7 is a front elevational view thereof.

Figure 8 is a longitudinal sectional view thereof.

Figure 9 is a longitudinal sectional view showing the key means between the tape drum and the weekday drum.

Referring now to the drawings with particular reference to Figures 1 through 9 I have illustrated the preferred embodiment of my invention as comprising a case 2 of suitable shape and material having a front glass 3 and face 4 with minute hand 6 and hour hand 8, the hour hand

2

motivated by tubular shaft 10 and the minute hand by the enclosed shaft 11. The shafts are journaled and powered by the clock work mechanism 12 at the rear of the case.

On the tubular shaft 10, the hour hand shaft, I provide a worm gear 14 driving a gear 16 on an operating shaft 18 journaled in brackets 20 and supplying the power for the calendar mechanism.

Within the case 2 I provide a pair of casings 22 and 24 which enclose an upper idler reel and a lower winding reel, for the tape 26. The tape may be of any suitable material such as metal or the like, and the tape is marked with the days of the year by month and day, as for instance January 29. The tape has at its sides series of openings 15 and indicia on the tape are visible through the glassed aperture 29 in the case 2.

The casings 22 and 24 are carried by shafts 30 and 32 of which shaft 30 is an idler and is journaled in brackets 34, and the shaft 32 is journaled in bracket 26. The shaft 32 is separable and the drive between the separable portions is effected through the clutch 35 comprising toothed disks 36 and a spring 38.

On the end of shaft 32 I employ a bevel gear 40 meshing with another bevel gear 42 on shaft 44 which has a gear 46 driven by worm gear 47 on the shaft 18.

A month and day indicating drum 48 has series of pins 50 engageable with the spaced apertures 15 on the tape, and this drum also has a gear ring 52, the drum being carried by a calendar drum shaft 54 journaled in bracket 55, and a weekday drum 56 is keyed to the drum 48 by keys 58. The weekday drum has indicia showing the days of the week also visible through the aperture 29 of case 2.

The shaft 54 is also provided with a drum 60 and a spring 62 confined by collar 63. On the end of shaft 18 I affix a gear segment 64, engageable intermittently with the gear ring 52. The shaft 18 rotates continuously while the gear segment rotates with the shaft engages the gear ring during a portion of its circular movement about the shaft 18.

The hour hand shaft being the slowest movement of the clock driven mechanism, is used to power the calendar device. Shaft 18 is ratioed to the hour hand shaft so that the shaft 18 makes one complete revolution every 24 hours, or every two revolutions of the hour hand shaft. The gear segment 64 is formed so that its gear contact arc comprises one-seventh of a circle or 51 and $\frac{3}{7}$ degrees and having seven teeth it will follow that

the gear segment will engage the gear ring 52 during one-seventh of its rotary movement therefore the month and day drum, and the weekday drum will move peripherally one-seventh of their circumference each twenty-four hour period. The movement of the month and day, and weekday drums requires three hours, 25 and $\frac{5}{7}$ minutes or one-seventh of the twenty-four hour period and it is preferred that this period be started at say 10:17 p. m. and the movement will be completed at 1:42 and $\frac{5}{7}$ minutes, a. m. the change in date and day therefore occurring when most people are asleep.

The reel in casing 22 is a dispensing reel and is not driven but may be rewound at the end of the year by a knob 27 and by releasing the reel in casing 24 on shaft 32 by knob 66, the tape is released from the lower casing 24. Should the clock have stopped for any length of time, as by a power failure, or failure to wind the clock, the day of the week and of the month may be inaccurate and the calendar drums may be set by means of the knobs referred to above, or by moving the tape on the drum 48.

Having thus fully described my invention what I claim as new and desire to secure by Letters Patent is:

1. In a calendar clock, the combination which comprises a clock works mechanism, a minute hand shaft extended from said mechanism, a tubular hour hand shaft also extended from said mechanism and positioned around the minute hand shaft, a case having a front wall with windows and a glass panel therein, a worm gear positioned on said hour hand shaft, an operating shaft journaled in said case, a gear mounted on said operating shaft and positioned to mesh with said worm gear, a calendar drum shaft spaced from and parallel to said operating shaft, said calendar drum shaft also journaled in said case, a week day drum mounted on said calendar drum shaft, a month and day indicating drum also mounted on said calendar drum shaft, said week day and month and day indicating drums being positioned to register with the windows in the front wall of the case, said month and day indicating drum being keyed to the shaft and also to said week day drum, a ring gear on said month and day indicating drum, a gear on said operating shaft positioned to mesh with the gear on said calendar drum, a tape having names of the months and the number of days in each month thereon, trained over said month and day indicating drum and carried by an upper idler reel and a lower winding reel, a lower shaft also parallel to and spaced from said operating shaft, said lower reel shaft also journaled in the case, transmission elements connecting said lower reel shaft to the operating shaft, said upper idler reel being mounted on the upper reel shaft and positioned to feed tape to said month and day indicating drum, and a spring actuated clutch mounted on said lower reel shaft and positioned to operatively connect the lower reel to

the lower reel shaft, said lower reel providing a tape winding reel and being journaled in said case and positioned to receive the lower end of the tape, said month and day indicating drum having spaced radially disposed pins thereon and said tape having openings therein positioned to register with the pins of the month and day indicating drum.

2. In a calendar clock, the combination which comprises a clock works mechanism, a minute hand shaft extended from said mechanism, a tubular hour hand shaft also extended from said mechanism and positioned around the minute hand shaft, a case having a front wall with windows and a glass panel therein, a worm gear positioned on said hour hand shaft, an operating shaft journaled in said case, a gear mounted on said operating shaft and positioned to mesh with said worm gear, a calendar drum shaft spaced from and parallel to said operating shaft, said calendar drum shaft also journaled in said case, a week day drum mounted on said calendar drum shaft, a month and day indicating drum also mounted on said calendar drum shaft, said week day and month and day indicating drums being positioned to register with the windows in the front wall of the case, said month and day indicating drum being keyed to the shaft and also to said week day drum, a ring gear on said month and day indicating drum, a gear on said operating shaft positioned to mesh with the gear on said calendar drum, a tape having names of the months and the number of days in each month thereon, trained over said month and day indicating drum and carried by an upper idler reel and a lower winding reel, a lower shaft also parallel to and spaced from said operating shaft, said lower reel shaft also journaled in the case, transmission elements connecting said lower reel shaft to the operating shaft, said upper idler reel being mounted on the upper reel shaft and positioned to feed tape to said month and day indicating drum, a spring actuated clutch mounted on said lower reel shaft and positioned to operatively connect the lower reel to the lower reel shaft, and a knob extended from the shaft upon which the upper reel is mounted for rewinding the tape, said month and day indicating drum having spaced radially disposed pins thereon and said tape having openings therein positioned to register with the pins of the month and day indicating drum.

VICTOR ANDERSON.
